US0D1033224S

(12) **United States Design Patent** (10) Patent No.: **US D1,033,224 S**
(45) Date of Patent: ** Jul. 2, 2024

(54) **DRAIN TUBING MANAGEMENT BOARD**

(71) Applicant: **Medline Industries, LP**, Northfield, IL (US)

(72) Inventors: **Connor Feeney**, Evanston, IL (US); **Andrew J. Mills**, Highland Park, IL (US)

(73) Assignee: **Medline Industries, LP**, Northfield, IL (US)

(**) Term: **15 Years**

(21) Appl. No.: **29/722,385**

(22) Filed: **Jan. 29, 2020**

(51) LOC (14) Cl. **24-02**

(52) U.S. Cl.

USPC **D24/128**

(57) **CLAIM**

The ornamental design for a drain tubing management board, as shown and described.

DESCRIPTION

FIG. 1 is a top, front perspective view of a drain tubing management board showing our new design;

FIG. 2 is a bottom, rear perspective view thereof;

FIG. 3 is a rear elevation view thereof;

FIG. 4 is a front elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines illustrate portions of the drain tubing management board that form no part of the claimed design.

1 Claim, 5 Drawing Sheets
